Primary Examiner—Susan J. Lucas*Assistant Examiner*—Jennifer Rivard(74) *Attorney, Agent, or Firm*—Stetina Brunda Garred & Brucker(57) **CLAIM**

The ornamental design for a push/pull latch, as shown and described.

DESCRIPTION

FIG. 1 is a front bottom perspective view of the push/pull latch of the present invention showing my new design with the phantom lines depicting solely environmental structure and forming no part of the claimed design;

FIG. 2 is a left side elevational view thereof, the right side elevational view is a mirror image;

FIG. 3 is a front elevational view thereof;

FIG. 4 is a top plan view thereof;

FIG. 5 is a rear elevational view thereof;

FIG. 6 is a top plan view of a second embodiment of the push/pull latch of the present invention showing my design with the phantom lines depicting solely environmental structure and forming no part of the claimed design;

FIG. 7 is a right side elevational view thereof, the left side elevational view is a mirror image; and,

FIG. 8 is a front elevational view thereof.

With the exception of the knob, the rear view of the second embodiment is identical to FIG. 5. The cross-sectional views are shown for convenience of illustration. In both embodiments, it is understood that the housings around the knobs are uniformly continuous.
